UNITED STATES PATENT OFFICE.

GARNET THOMAS GALLEY, OF LEYTONSTONE, ENGLAND, ASSIGNOR TO ALERT ADVERTISING COMPANY, LIMITED, OF LONDON, ENGLAND.

ADVERTISING APPARATUS.

Application filed September 26, 1923. Serial No. 664,892.

This invention relates to advertising apparatus wherein advertisements provided with movable elements and carried by an intermittently movable frame have such elements automatically moved to represent life-like actions during periods when such advertisements are in the displayed position.

The present invention consists essentially in providing each movable element in an advertisement with an operatively connected and pivoted comb provided with teeth the pitch and number of which are predetermined for each comb according to the extent and periodicity of movement required, the necessary movement being imparted to each movable element of each advertisement by rocking the respective combs about their pivots by means of laterally moving forks which are moved across and in contact with the teeth of the combs when the particular advertisement is in the displayed position.

In order that the invention may be clearly understood an embodiment of the same will now be described by aid of the accompanying drawings in which:—

Fig. 1 is a part sectional elevation of an advertising apparatus according to this invention.

Fig. 2 is a plan of the same with the top removed to expose the operating mechanism and the advertisement carrying frames and

Fig. 3 is a fragmentary perspective view of the mechanism for both intermittently moving the frames and for operating the movable elements of the advertisements.

Fig. 4 is a top plan view of the comb mechanism of my device.

Fig. 5 is a side elevation of the comb mechanism of my device.

Fig. 6 is a detailed view of one of the picture groups.

The apparatus shown in the drawings comprises a cabinet 1 having a display opening 2 and conveniently situated electric lamps 3. Mounted vertically within this cabinet and upon a common axis are a pair of concentric frame members 4 and 5 the inner frame member 4 being of polygonal shape and the outer frame member 5 being circular. Each side of the inner frame member is adapted to receive an advertisement each of which comprises one or more movable elements forming part of the picture or representation. The outer frame

member is only provided with half the number of advertisements carried by the inner frame member thus leaving, in the present example three open spaces 6.

As shown in Fig. 1 each of the movable elements in the advertisements carried by the inner frame member is operatively connected to a separate comb 7 through the medium of a crank 8 and rod 9 the lower end of which rod is connected to one arm of a lever the other arm of which carries the comb shaped members 7. This lever is fulcrumed upon a pivot pin 10 extending laterally across the back of each advertisement. In the case of an advertisement having only one movable element only one comb is required, the number of combs depending upon the number of movable elements there are in the advertisement. In the example illustrated in Fig. 1 there are two movable elements and therefore two comb-shaped members.

These comb-shaped members are provided with teeth 11 the pitch and number of which are predetermined for each comb shaped members according to the extent and periodicity of movement required. The necessary movement is imparted by rocking the comb-shaped members about their pivots 10 by means of laterally moving forks 12 which are moved across and in contact with the teeth of the comb shaped members when the particular advertisement is in the displayed position before the opening 2. The forks 12 which correspond in number and position with the various comb-shaped members to be operated are carried by a vertical frame 13 the lower end of which is provided with a foot 14 which rests upon and is adapted to slide on a table 15.

Extending rearwardly from a point adjacent the upper end of the vertical frame 13 is a slotted bar 16 which carries at right angles to it a guide rod 17 the extremities of which slidably engage in holes in a pair of upstanding frame members 18. The slot in the bar 16 is engaged by a pin 19 carried by and projecting upwardly from one end of a crank arm 20. This arm is double ended and is attached to a disc 21, the other end of said arm being provided with a depending pin 22, which engages the slots 23 of a Geneva wheel 24. By these means rotation of the arm 20 serves to reciprocate the ver-

tical frame 13 and intermittently rotate the Geneva wheel 24. This intermittent movement is transmitted to the frame members 4 and 5 as will now appear.

5 The frame members 4 and 5 are mounted upon concentric spindles 25 and 26 respectively each of which is provided with a separate Geneva wheel 24. These wheels in turn have associated with them double 10 armed cranks 20 and discs 21 the peripheries of which fit closely against the concave surfaces 27 of the Geneva wheels. The double armed crank associated with the Geneva wheel which is mounted upon the spindle 26 carrying the outer frame member 5 is provided at both ends with upstanding pins 28 which engage the slots of the associated Geneva wheel and serve to intermittently rotate such wheel two revolutions to one 15 revolution of the upper Geneva wheel carried by the other spindle 25.

By these means the inner frame member 4 is permitted to have in the present example, six advertisements to three on the outer 20 frame member, which former advertisements are brought into position in front of the display opening 2 during the display of one of the advertisements on the outer frame member. Thus the rotation of the inner frame member is invisible from the exterior of the cabinet. The display of the advertisements on the inner frame member takes place each time one of the open spaces 6 comes opposite the display opening.

35 As will have been understood the operation of the movable elements of the advertisements on the inner frame member is effected in consequence of the engagement between the forks 12 and the teeth on the 40 combs 7 during the reciprocation of such forks.

The mechanism is driven, in the present example by means of an electric motor 29 which drives the spindle carrying the discs 45 21 through the medium of a worm wheel 30 mounted upon said spindle, a worm 31 mounted upon a spindle 32 which spindle in turn carries a pulley 33 which receives the drive from the motor through a belt 34. 50 Any other form of mechanical drive may however be adopted.

In the drawings it will be noticed that the serrated comb-shaped member 11 is attached to a pivoting rod 10 by means of 55 arms 10^a. The rod 10 in turn is connected to a shaft 9^a by means of a connecting rod 9 and crank arms 8 and 8^a. The result is that when the forks 12 (see Fig. 1) are reciprocated across and in engagement with the 60 teeth on the comb-shaped member 11 such comb-shaped member is turned about and with the rod 10. This motion, through the rod 9 and crank arms 8 and 8^a is transmitted to the shaft 9^a which is thereby partially 65 rotated or oscillated and with the movable

part 9^b of the advertisement carried thereby.

What I claim and desire to secure by Letters Patent is:—

1. In an advertising apparatus of the type specified the combination with an intermittently rotating inner frame carrying picture groups and a stationary outer frame having a display opening of an intermediately arranged intermittently rotating frame having alternating walls and openings and means for intermittently rotating the said intermediate and inner frames in such manner that a wall of the intermediate frame is opposite the display opening in the stationary outer frame when the inner frame is being moved, movable elements forming part of the pictures in the groups carried by the inner frame and means for operating the movable elements of each picture when the picture is opposite the display opening in the stationary outer frame.

2. In an advertising device of the type described, the combination with picture groups and a central pillar about which they rotate, of a frame carrying said groups adapted to rotate about said pillar; comb shaped members attached to said frame, each of said comb shaped members being adapted to move portions of its respective group; a central member provided with arms adapted to actuate successively said comb shaped members; an outer rotatable frame mounted upon said pillar and provided with openings; and means adapted to rotate said central frame into group display positions and subsequently rotate said outer frame to expose to view a group through one of said openings.

3. In an advertising apparatus of the type specified the combination with an inner frame carrying picture group and mounted upon and rotatable with a central spindle and a stationary outer frame having a display opening of an intermediately arranged frame mounted upon and rotatable with a tubular spindle fitting as a concentric sleeve upon the spindle of the inner frame means for intermittently rotating both of said inner and intermediate frames comprising two sets of Geneva wheels one operating on one shaft and the other operating on the other shaft, movable elements forming part of the pictures in the groups carried by the inner frame and means for operating the movable elements of each picture when the picture is opposite the display opening in the stationary outer frame.

4. In an advertising apparatus of the type specified the combination with an inner frame carrying picture groups and mounted upon and rotatable with a central spindle and a stationary outer frame having a display opening of an intermediately arranged frame mounted upon and rotatable with a tubular spindle fitting as a concentric sleeve upon the spindle of the inner frame means

for intermittently rotating both of said inner and intermediate frames comprising two sets of Geneva wheels one operating on one shaft and the other operating on the other
5 shaft, movable elements forming part of the picture in the groups carried by the inner frame and means for operating the movable elements of each picture when the picture is opposite the display opening in the stationary outer frame comprising pivoted combs associated with each of the movable elements in a picture, forks, and means for reciprocating said forks across and in contact with the combs so as to rock the same
15 about their pivots and means for transmitting such movement to the movable elements of the picture.

5. In an advertising apparatus of the type specified the combination with an inner frame carrying picture groups and mounted upon and rotatable with a central spindle and a stationary outer frame having a dis-

play opening of an intermediately arranged frame mounted upon and rotatable with a tubular spindle fitting as a concentric sleeve 25 upon the spindle of the inner frame means for intermittently rotating both of said inner and intermediate frames comprising two sets of Geneva wheels one operating on one shaft and the other operating on the other 30 shaft, movable elements forming part of the pictures in the groups carried by the inner frame and means for operating the movable elements of each picture when the picture is opposite the display opening in the stationary outer frame and a sliding carriage carrying said forks a crank for reciprocating said carriage and means for driving said crank such means also serving to drive the Geneva wheel mechanism for intermittently rotating 40 the inner and intermediate frames.

In witness whereof I affix my signature.

GARNET THOMAS GALLEY.
